UNITED STATES PATENT OFFICE.

JOHN L. WILSON, OF BUFFALO, MONTANA.

HEN'S NEST.

1,194,263.

Specification of Letters Patent. Patented Aug. 8, 1916.

Application filed May 21, 1915. Serial No. 29,571.

To all whom it may concern:

Be it known that I, JOHN L. WILSON, a citizen of the United States, residing at Buffalo, in the county of Fergus and State 5 of Montana, have invented certain new and useful Improvements in Hens' Nests, of which the following is a specification.

This invention relates to an improved hen's nest and the principal object of the invention is to provide a nest so constructed that the front doors will be closed when the hen enters the nest and open when the hen leaves the nest thus preventing other hens from interfering with the hen occupying the nest.

15 Another object of the invention is to provide improved operating means for the sliding doors of the nest, one of the operating platforms serving to close the doors and the other serving to open the same.

20 Another object of the invention is to provide a nest which will be strong and durable and which can be very easily cleaned and thus kept sanitary.

Another object of the invention is to provide a nest which will be well ventilated and which is so constructed that easy access may be had to the interior of the same.

Another object of the invention is to provide a nest which will be of a relatively cheap 30 construction and thus capable of being placed upon the market at a small cost.

This invention is illustrated in the accompanying drawings, wherein:

Figure 1 is a vertical longitudinal sectional view through the improved nest. Fig. 2 is a front elevation of the nest with the doors open. Fig. 3 is a front elevation of the nest with the doors closed. Fig. 4 is a view taken along the line 4-4 of Fig. 1. 40 with the cross bars forming the upper wall broken away.

The housing or body portion comprises the side walls which are formed of frame 10 provided with vertically extending rods 45 or bars 11 and connected by the cross rods 12 which cross rods form the top and bottom and rear walls of the housing. The vertical rods 13 which form the front wall are separated a sufficient distance to provide a passageway as clearly shown in Fig. 2 thus permitting the hen to easily pass into and out of the nest.

It is desired to have the doors 14 which are slidably mounted upon the rods 15 and 55 having their lower ends curved and positioned behind the guard rails 15', open and

close at the proper time and therefore there has been provided pivotally mounted platforms 16 and 17 which are positioned within the housing in front of the compartment 18 and connected with the doors by means of the lines 19 and 20. The lines 19 extend from the platform 16 and are connected with the outer edge portions of the sliding doors and lines 20 extend from the platform 17 and are connected with the inner edge portions of the door so that when pressure is applied to the platform 16 the doors will be opened and when pressure is applied to the platform 17 the doors will be closed.

When this nest is in use a suitable receptacle such as a box or any other receptacle can be placed in the compartment 18 to hold the straw forming the nest or if desired the straw itself can be directly placed in the compartment. The cover 21 is provided so that easy access may be had to the compartment 18 both for removing the eggs and also for cleaning the nest and replenishing the straw when necessary. These doors will normally be opened as shown in Fig. 2 and the hen can therefore pass through the passageway into the housing. The hen will first pass across the platform 16 and will then set upon the platform 17. The weight of the hen will cause the platform 16 to move downwardly thus drawing upon the line 20 and causing the doors to slide to the closed position shown in Fig. 3. When the hen desires to leave the nest it will walk across the platform 17 and will then step upon the platform 16, the weight of the hen moving the platform 16 downwardly to draw upon the line 19 and return the doors to the open position. Therefore the doors will normally remain open and will be closed when the hen has entered the nest and opened again when she desires to leave the nest. If it is desired to clean the nest it can be easily done since access to the compartment 18 can be had through the opening closed by the cover 21. It should be further noted that since this nest has an open construction it will be well ventilated and therefore lice and other vermin will not be as liable to infest the nest.

What is claimed is:

A nest comprising a body portion having a front wall provided with an inlet opening, an upper bar extending transversely across the front wall in spaced relation thereto, a lower bar extending across the front wall in spaced relation thereto, doors having ver-

5 tically extending bars slidably connected with the upper bar extending across the front wall and having their lower end portions bent to extend beneath the lower bar extending across the front wall, actuating platforms mounted in said body portion, and flexible means leading from said platforms and connected with said doors where-

by movement of said platforms will slide said doors upon said upper bar. 13

In testimony whereof I affix my signature in presence of two witnesses.

JOHN L. WILSON.
